UNITED STATES PATENT OFFICE.

JOHN W. ESTES, OF ST. LOUIS, MISSOURI.

DESIGN FOR A TABLE.

SPECIFICATION forming part of Design No. 35,728, dated February 11, 1902.

Application filed December 12, 1901. Serial No. 85,701. Term of patent 14 years.

To all whom it may concern:

Be it known that I, JOHN W. ESTES, a citizen of the United States, and a resident of St. Louis, Missouri, have invented and produced 5 a new and original Design for a Table, of which the following is a specification.

Figure 1 is a top plan view of the table embodying my new design. Fig. 2 is a view in elevation of the table. Fig. 3 is a sectional 10 elevation.

As shown in the drawings, the leading or material features of my new design consist of the circular bottom 4, the legs 5, supporting the bottom and extending upwardly a short 15 distance from the bottom, and the curved por-

tions 6, inserted between the legs and above the bottom, the upper edges of said curved portion being on a level with the upper ends of the legs and the transparent top 7 resting upon the legs and the curved portions 6. The 20 top portion is larger than the bottom portion 4, so that the top extends outwardly beyond the curved portions 6.

I claim—

The design for a table, substantially as here- 25 in shown and described.

JOHN W. ESTES.
